UNITED STATES PATENT OFFICE.

HARRY L. VAN ZILE AND THOMAS A. LEWIS, OF NEW YORK, N. Y.; SAID LEWIS
ASSIGNOR TO SAID VAN ZILE.

VENTILATING APPARATUS.

1,211,900.

Specification of Letters Patent.

Patented Jan. 9, 1917.

Application filed October 10, 1914. Serial No. 866,084.

To all whom it may concern:

Be it known that we, HARRY L. VAN ZILE and THOMAS A. LEWIS, citizens of the United States, and residents of the borough of Manhattan, in the county of New York and State of New York, have invented certain new and useful Improvements in Ventilating Apparatus, of which the following is a specification.

10 This invention relates to an improved ventilating apparatus and has particular reference to the regulation of natural air-currents entering a room.

The main object of the invention is to produce a ventilator possessing the following advantages, namely: first, that it receives the air current from the outside tangentially in the direction in which the air flows, so that the greatest aggregate quantity thereof is collected; secondly, that it separates this current into a plurality of subordinate parallel layers which are protected from the main body of the oncoming air, as well as from frictional interference of one with the other; thirdly, that it conducts these layers simultaneously along quadri-sectoral bends of uniform shape causing their direction of motion to be changed with the least loss of speed; fourthly, that the exits through which the layers respectively issue are arranged adjacent to one another in the same plane, substantially at right angles to the plane of entrance of the air, in such a way that the juxtaposed layers will collectively continue their travel upward as far as practicable away from the ventilator before being permitted finally to diffuse into the room.

Another object is the production of a ventilator characterized by the advantages above enumerated which shall be of light and rigid construction, and also economical to manufacture.

Still another object is to provide a ventilating device of the type hereinbefore outlined, wherein the passages formed by or between the quadri-sectoral bends may be opened for the flow of air therethrough gradually, singly, alternately, consecutively, serially, or collectively, so as to regulate the volume of air entering the room, in any desirable manner.

A further object is the provision of an air duct combined or formed with the aforesaid type of ventilator so as to collect and guide

the oncoming air to the ingress ends of the 55 said passages, located against the face of the duct turned toward the interior of the apartment.

A still further object is to provide the said air-duct with guide vanes adapted to 60 coöperate at their inner ends with the aforementioned bends that form the passages in the ventilator, and projected at their outer ends into the path of a closure capable of either shutting off or admitting the air to 65 the said vanes, or even entirely blocking the outer entrance to the air duct, as may be required.

A still further object is to provide the ventilator and duct thereof with means operable from within the room whereby the admission of air to the duct, guide vanes, and ventilator bends can be satisfactorily controlled.

Further objects and features of novelty 75 will become apparent as the specification proceeds.

Generally described, the invention comprises a duct or casing passing through the wall of a building; a plurality of guide 80 vanes within the casing spaced apart from one another and having a closure coöperating therewith to open the entrance to the passages between the vanes in sequence, from top downwardly, and that of the casing as 85 well; a current-distributer composed of quadrantly bent plates set at intervals one from the other to form channels between them and having their entrance and exit ends alined in vertical and horizontal planes 90 respectively, the entrance ends receiving the air from the said passages, and the exit ends delivering it within the room vertically along the adjacent side thereof; a slide inserted between the guide-vanes and the dis- 95 tributer plates operating to admit the air into the said channels successively, from the lowermost vane upwardly, or to exclude it therefrom upon being moved in the reverse direction, and means operable inside the 100 apartment for graduating the volume of air permitted to flow in through the ventilator.

The advantages of the invention as here outlined are best realized when all its features and instrumentalities are combined in 105 the one and same structure, but, useful devices may be produced embodying less than the whole.

It will be obvious to those skilled in the art to which the invention appertains, upon becoming conversant with the details thereof, that the same may be incorporated in several different constructions. The accompanying drawing, therefore, is submitted herewith as showing the preferred exemplification of the invention.

In the said drawing: Figure 1 is a fragmentary perspective view of the invention, parts being omitted or shown in section; Fig. 2 is a similar view of the current distributor alone; Fig. 3 is a fragmentary plan view, showing the right-hand portion of the 10 ventilator, taken from the interior of the apartment; Fig. 4 is a fragmentary rear elevation of the same, this being the left of the ventilator, when viewed from the exterior of the building; Fig. 5 is a similar elevation of 15 the middle portion of the apparatus, one of the parts indicated in the preceding figure being shown in a changed position; Fig. 6 is a fragmentary front elevation of the latter-named portion, looking in the opposite direction, the distributor being omitted; Fig. 7 is a fragmentary front elevation of the inner 20 right-hand portion of the ventilator, corresponding to the plan shown in Fig. 3; Fig. 8 is a transverse sectional elevation of the 25 whole apparatus illustrated by the preceding views; and Fig. 9 is a cross-sectional elevation of a modified form of the invention.

In these several views, the numeral "11" 30 represents an air-collector, preferably in the shape of a duct or casing, which is set in the masonry or other material constituting the wall of a building, as at A Fig. 8, so as to permit fresh air to pass through the same. 35 This collector which may also be termed a wind-box, comprises a top 12, bottom 13, and ends 14, 15. Overlapping flanges 16, 17, join the said parts at the front and rear respectively, these flanges surrounding oppositely-disposed openings 18, 19.

In practice, the upper margin of the lower front flange (looking from the outside) is beveled to an edge 20, the purpose of which will presently appear. Within the collector 40 11, substantially in alignment with the said edge 20, is hinged a door 25, acting as a closure for the outer opening 18, when placed in a vertical position, as seen in Fig. 5. The lower edge of this door is rolled or beaded outwardly, as at 26, and also made to contact with the before mentioned edge 20, in such a manner that when the door is swung from its open, horizontal position, shown in Figs. 4 and 8, any snow or sleet lodged thereon will readily be scraped off. At the ends 45 of the door 25 are formed hubs 27, which partake of the curvature of the rolled-over edge 26 thereof. Pivot pins 28, secured in these hubs by means of set-screws 29, are journalled in the end walls of the collector

11. Upon withdrawing the said pins 28 inwardly of the latter, the door 25 may be removed. The side and top edges of this door, when closed contact with the over-lapping flanges 16, 17 so as to keep out rain and snow from the interior of the air-collector. It is conceivable that the door 25 could be sustained directly in the wall opening without the adjunct of the casing 11. Substantially central of the said door is formed a hollow boss 32, within and across the sides of which is fitted a pin 33. The latter is connected by means of a link 34, to a spindle 35, in such a manner that when the said spindle is manipulated one way or the other, the door will either stand vertical or lie horizontally or occupy some intermediate position, for instance, as is indicated at b and c Fig. 8. To adapt it for its function of raising and lowering the door 25, the said spindle 35 may be threaded (multiple if desired to effect quick movement) and have its end portions journaled in bearings 36, 37 formed with the front and rear flanges 16, 17, respectively. See Figs. 5, 6 and 8. As here shown, a hand-wheel 38, or other grip, is mounted on the inner reduced extremity 39 of the spindle, in a convenient position to be operated from within the building. The hub of the said hand-wheel co-acts with a fixed collar 40 in holding the spindle from axial displacement. A nut or internally threaded sleeve 41 is in engagement with the threaded part of the spindle and is translatable thereon axially when the latter is rotated. Trunnions 42 extending from opposite sides of the sleeve 41, are engaged by a fork or bifurcation 43 at the adjoining end of the link 34. The outward extreme travel of the link-pin 33, corresponding to the closed position of the door 25, is indicated at d Fig. 8. The spindle 35, traveling nut 41, and the inner or lower end of the link 34 are contained in a trough-shaped extension 44, depending from the bottom 13 of the air-collector 11. Within the said collector are placed, at suitable intervals apart, a plurality of horizontal shelf-like vanes 47, which are practically extensions of other vanes, to be more fully referred to hereinafter. The said vanes 47 are held to the ends 14, 15 of the collector by a pair of oppositely-located, inwardly flanged carriers 48, one of which is shown in Fig. 8, the flanges 49 of these carriers being slotted horizontally to conform to the spacing between the vanes, which latter are inserted and appropriately secured at their inner ends in opposite slits. The inner edges of these vanes 47 terminate on a line approximately flush with the adjoining face of the inside flange 17 of the collector, while their outer edges follow the arcuate path described by the free edge of the door 25 swinging upon its pivot 28. Thus, it will be observed, as this door is moved inwardly 120

from a closed position, the spaces between the vanes 47 are uncovered one after the other from the top downwardly.

As shown, the uppermost vane 47 is substantially on a level with the top margin of the outer opening 18, and the forward edge thereof may be turned up as at 50, to prevent an incoming air-current from backing up above this vane. Adjacent to, or rather 10 spaced from the inner edges of the said vanes a sufficient distance to permit the insertion of a slide 54, is an air-distributer 55. The said slide may be of any suitable construction. As shown, it consists of a frame 15 56 with a glass or other panel 57, lifting hooks 58 being provided for convenience in raising or lowering the same. It will be noticed that the amount of air passing through the duct, casing, collecting opening 20 or like element constituting the body of the before described collector, and between the said vanes, into the distributer above mentioned, can be regulated in three ways, to wit: first by the slide 54, which uncovers 25 the vanes one after another from the bottom of both collector and distributer upwardly; second, by the previously described swinging door 25, which opens the entrance to the upper vanes first and thence to the others 30 downwardly; and third, by working the door and the slide conjointly one with the other. By reason of this arrangement, it is possible to conduct the air between one or more sets of vanes, top or bottom, at 35 option. In some instances, it may be found advantageous to use the swinging door in such way as to shut out rain or snow, and to do the regulating by the slide; while in other cases, the control of the air may be 40 had through the agency of the door; and under certain circumstances the door and the slide can be utilized each as the governing medium on its own side of the duct.

Although a separate slide is shown in conjunction with the ventilator, no limitation in this respect is thereby intended, as the present invention purports to use an ordinary window-sash to vary the ingress or egress of air to or from the distributer. As seen particularly in Figs. 3 and 7, at one side thereof, the slide described can be maintained in proper alignment, within or relatively to the ventilator, by means of lateral retainers 51. These may be attached to the vertically 55 extending margins of the inner face of the rear flange 17, or to any other convenient primary support, by means of screws 62, for instance. The inner edge of each retainer is offset at 63, to serve as a ledge, the purpose whereof will be fully set forth herein-after.

Whether or not the slide 54 be used the bottom part of the distributer 55 is turned so as to receive the air from the aforementioned collector, or the guide vanes thereof,

which incidentally may be made integral with the said distributer, as the case may be. In its preferred embodiment, the said distributer comprises quadri-sectoral end pieces 67, between which are confined concentrically disposed quadrantal curved vanes 68. These vanes are spaced apart to form between them a series of gradual substantially 70 90° bends affording correspondingly shaped passages 69, arranged so that the shortest 75 and sharpest bend is uppermost and the succeeding bends follow one after the other, with the intervening passages, in the order of their respective lengths. The receiving ends of the said passages 69 are disposed 80 one above another substantially in the same vertical plane, and also tangentially to the oncoming air-currents, so as to collect the greatest quantity thereof and guide the same gradually for their entire travel through 85 the distributer.

Due to the fact that the air-currents, flowing from the exterior into the apartment to be ventilated, are divided into a plurality of subordinate parallel layers by the vanes, 90 they are prevented from interfering with one another, and the internal friction of the air traveling along the bends 69 is accordingly reduced. Besides, the particles of the air composing the said layers are protected 95 from the main body of the oncoming air as soon as they have passed beyond the exposed surface of the lower one of the pair of vanes forming each passage. Thus, only a comparatively small portion of the air passing 100 between the vanes is subjected to direct impingement of the air particles next following. From the moment the air which has entered between a pair of adjacent vanes passes beyond an area on the lower vane 105 of the pair bounded by an extended line tangential to the upper vane, it becomes free from this impinging action of the following air, which then only serves to urge the protected volume of air farther ahead.

The quantity of air flowing between the vanes 68 of the distributer is guided by their gradually changing curvature in such a manner that the deviation thereof is produced with the least loss of velocity. All of the 110 separated air-layers issue in one and the same plane, which is at substantially right angles to the plane of entrance to the passages between the vanes. This disposition of vanes at the exit ends of the passages 115 taken in conjunction with the unimpeded speed of the air flowing therethrough, will cause the layers again combining at the issue points to continue their travel collectively to the greatest possible extent upward, before 120 the air becomes diffused and commingles with the other air within the room. By thus favoring and maintaining the speed of the air passing through the ventilator into the room to the farthest extent, direct drafts 125 130

upon the occupants thereof are avoided. If the ventilator is placed in front of a window or other aperture in the wall of an apartment, such an aperture can be left considerably open without discomfort, because the upwardly-flowing air streams act as a screen or curtain in shutting out the external air that could otherwise be directly blown in.

The before-mentioned vanes 68 have their longitudinal edges beaded or folded over, as at 71, to constitute reinforcements therefor. The ends of these reinforcing beads are clasped within apertures 72, provided in lips 73, depending from flanges 74, which are formed on the radial sides of the lateral pieces 67 and extended at substantially right angles to the same. The remaining quadrant sides of the said lateral pieces are provided with a corresponding flange 75, to which is riveted or otherwise secured the longest and outermost vane 68^a, as shown at 76 (Fig. 2). At the apex of the quadrisection, or juncture of the flanges 74 in opposite end-pieces, is attached a right-angular brace 77, which together with the aforementioned outermost vane 68^a maintains the intermediate vanes 68 in their proper position. Where the vanes comprised in the distributor are of considerable length, it is desirable to hold them together, for instance by a tie 80, extending between the outer vane 68^a and brace 77. This tie preferably consists of a channeled bar, as shown, the depending flanges of which take over the beaded edges of the intermediate vanes, substantially in the manner set forth relative to the end or lateral pieces 67. A similar tie may be used in connection with the guide vanes 47 within the air-collector, as shown at 81, Fig. 6, excepting that the latter-named tie must be curved to conform to the path followed by the free edge of the closure 25, instead of being straight like the tie 80 in Fig. 2.

Constructed in accordance with the detailed description hereinbefore given, the air-distributer 55 constitutes a rigid, light and economically manufactured device for the purposes set forth. To enable the same to be readily placed in and removed from the position represented in Figs. 3, 7 and 8, a convenient means, in the shape of keepers 85, is provided. As seen at 86, Fig. 3 the nose portion of the keeper there shown takes back of the ledge 63 of the retainer 61. Screws 87, engaging suitable slots 84 either in the flat body portion of the keeper or in the angle-brace 77, permit lateral adjustment of the former to make up for any slight variations in construction or assembling.

As illustrated in Fig. 8 particularly, it will be noticed that the slide 54 and the distributor 55 rest with their lower edges upon a shelf-like projection 88, extending 65 into the room from the lower part of the in-

side flange 17. In order to make a wind-proof contact between the bottom of the distributor and this shelf 88, a packing strip 89 of felt, india-rubber, or other suitable material, may be attached to the adjacent edge of the distributor's outermost vane 68^a. It is obvious that if the slide 54 is omitted, the distributor itself can be placed bodily against the inner flange 17 of the air-collector. 75

Fig. 3 indicates how a duct or casing, designed to fill the office of an air-collector, can be made of a plurality of parts, for instance, two as shown. These parts may be united on a line 91, and held together by a 80 threaded rod or bolt 92, one at each end if desired.

In the modified form of the invention represented by Fig. 9, the distributor 55^a is carried by, or carries, a flange 95, which is 85 placed in sliding engagement with the inner face of the collector 11^a, so as to bring a greater or less number of the passages 68^b into communication with the said collector, and in this manner control the amount of 90 air flowing through the said distributor. As a means of holding the said flange 95 with the distributor in the position thereto assigned, a screw 96 is shown. Another screw 97, or equivalent device, may be employed to hold the upper portion of this flanged air-distributer 55^a up against the air-collector 11^a. 95

It will be observed that the before described vanes 68 constitute a series of concentric arcuate deflectors that are spaced or separated from one another to form air passages therebetween. This series is removably supported adjacent to the ventilating orifice or air inlet previously mentioned, 100 and is controlled by the slideable closure 54, which successively traverses the end of the deflectors as it moves in either direction. In practice, the form of ventilating apparatus here referred to is considered as best 110 realizing the advantages of the invention. 105

Having described our invention, what we claim, and desire to secure by Letters Patent is:—

1. A ventilating apparatus including, in 115 combination, a series of concentric arcuate deflectors spaced to form air passages therebetween, means for supporting said deflectors adjacent to a ventilating orifice, and means for opening or closing said air passages successively.

2. A ventilating apparatus including, in combination, a series of concentric arcuate deflectors of progressively increasing lengths 120 spaced to form air passages therebetween, means for supporting said deflectors adjacent to a ventilating orifice, and a slideable member for controlling the flow through said passages serially from the longest to the shortest in one direction, and to close 125 130

the same in reverse order when moved in the opposite direction.

3. A ventilating apparatus including, in combination, a series of concentric arcuate deflectors spaced to form air passages of unequal lengths therebetween, means for supporting said deflectors adjacent to a ventilating orifice, said passages having their entrance ends superposed in the same vertical plane so as to receive the air tangentially from said orifice in horizontal layers, and their exit ends disposed one behind another in the same horizontal plane for delivering the air in parallel vertical layers supporting each other, and a closure at said entrance ends operable to open or close them serially.
4. A ventilating apparatus including, in

combination, a series of concentric arcuate deflectors separated from one another so as to form air passages therebetween, means for removably supporting said series of deflectors in spaced relation to a ventilating orifice, and a slidable element operable in the space between the latter and the deflectors to establish or cut off the flow of air therethrough.

Signed at the borough of Manhattan in the county of New York and State of New York this 8th day of October A. D. 1914.
